UNITED STATES PATENT OFFICE.

EDWARD FRANCIS BERRY, OF NEW ORLEANS, LOUISIANA.

FLEXIBLE JOINT.

1,153,187.

Specification of Letters Patent. Patented Sept. 14, 1915.

Application filed August 5, 1913. Serial No. 783,179.

To all whom it may concern:

Be it known that I, EDWARD F. BERRY, a citizen of the United States, residing at New Orleans, in the parish of Orleans and State of Louisiana, have invented certain new and useful Improvements in Flexible Joints, of which the following is a specification, reference being had therein to the accompanying drawing.

10 This invention relates to improvements in flexible joints, more particularly designed for use in connection with dredging pipe sections of that type disclosed in my Patent No. 1076738, of October 28, 1913, wherein the broad characteristics of the present coupling, as distinguished from the improvements hereinafter set forth, are claimed, and hence not included in the claims annexed hereto.

20 The present invention has for its object the provision of improvements constituting a practical, indestructible, flexible coupling, permitting yieldability of the parts in substantially any direction laterally and longitudinally of the coupled pipe sections, while preserving at all times the sealed relation between said sections irrespective of the adjustment or deflection thereof; and more specifically the formation of the packing members to secure the result thus stated; the means for fastening the packing to the members carrying the same; and means for preventing undue, lengthwise separation of the pipe sections to overcome any liability of the packing member being unseated with reference to the surface of the parts over which free portions of the packing move in sealing engagement therewith.

Although the improvements herein to be 40 protected may be incorporated in various embodiments of the invention, as will be apparent to persons skilled in the art to which the invention relates, I believe it will herein be necessary to illustrate but the preferred 45 embodiment thereof, and from which the improvements may be understood when considered in connection with the detail description hereinafter contained.

In the accompanying drawings forming a 50 part hereof, Figure 1 is a side elevation of the coupling complete; Fig. 2 is a longitudinal horizontal sectional view of the same, Figs. 3 and 4 are respectively, sectional

views of two of the coupling members, Fig. 5 is an end elevation looking at the larger 55 end of Fig. 3, Fig. 6 is an enlarged detail sectional view to clearly illustrate one of the packing members.

Referring more specifically to the drawings wherein like reference characters designate corresponding parts in the several views, A and B represent the adjacent ends of dredging pipe sections, adapted to be flexibly coupled together, and C, D and E, are coupling members, the members C and E being of a relatively fixed nature with reference to the pipe sections A and B, and the member D being of a relatively floating nature, that is not fixed with reference to the members C and E and dredging sections 70 A and B. The members C and E are connected to the sections A and B through the medium of flanges or collars a, c, b and e respectively, bolted together, as at F and G, with suitably interposed packing f and g, 75 clearly illustrated in Fig. 2. The coupling member C is truly cylindrical, while the members D and E are of sinuous formation to provide enlarged end portions d' and e' respectively, and in the case of the floating member D, a reduced end portion d''. The reduced end portion of the floating coupling member D is adapted to fit in the enlarged end portion e' of the member E, while the larger end portion d' thereof receives the 85 near end of the cylindrical member C.

I prefer to seal the coupling members by suitable packing arranged at the opposite ends of the sinuous coupling member D, one packing member exteriorly of the smaller 90 end of said member, and the other packing member interiorly of the larger end thereof, so that the former will engage the inner surface of the enlarged end e' of the member E, and the latter the inner surface of the enlarged end d' of the member D. The packing members are structurally the same in each instance, as indicated at H and I, Fig. 2, so that a specific description of one packing, as clearly shown in detail, Fig. 6 will 100 suffice for both.

Referring to Fig. 6, it will be seen that the packing member H, preferably of rubber, is of a cup formation, having a thickened base portion h, and an annular flange h' of pure 105 rubber projecting outwardly from the base,

at approximately right angles to the base, so as to provide a large surface contact between the flanges h' and the inner surface of the enlarged portion e' of the coupling member E, against which it engages, this contact extending from the end of the flange to the base portion, as shown.

For a purpose as will presently appear, the flange h' gradually reduces in thickness toward the free marginal edge h'' thereof, and this free edge projects toward the outlet end of the dredging pipe, in the direction of the flow of the pipe contents therefrom.

To secure the packing in place as well as reinforce the base portion thereof, I provide at the end of the coupling member D, or at the end of the member C, as the case may be, a clamping ring J, and inwardly thereof, an angular ring K, having an outwardly projecting flange k and a slotted base flange k' , for the reception of fastening devices, such as screws L, the slots k' affording a means of adjustment to position the ring K on the coupling member to which it is attached. The base portion h of the packing is interposed between the rings J and K, and the same is rigidly secured in place by means of fastening devices, such as screws, rivets, or the like M, passing through the rings J and K, and binding the base h of the packing therebetween and with the inner edge of the packing held firmly against the surface of the member D, or other member to which the packing is fastened.

From the construction thus far defined, it will be appreciated that the intermediate or floating characteristic of the member D, will permit lateral deflection and flexibility of the dredging pipe, as an entirety, as well as elongation and contraction of the interfitting sections, the parts being normally maintained in a contracted relation by means of springs N, engaging eyes n , n' on the coupling members D and E, and other springs O, engaging eyes o , o' on the members D and C, the latter being formed in the bolts F, utilized to fasten the pipe section A and coupling member C together, as hereinabove explained. There are preferably four springs, N and O, in each set, as will appear in Figs. 1, 2 and 5, although the number will vary as may be in keeping with the demands of any particular service.

To resist undue elongation of the dredging pipe against the resistance of the springs N and O which would result in the withdrawal of the packing members H and I, from the members D and E, as is obvious, I form the coupling members D and E with annular projecting parts or flanges constituting shoulders P and Q, the same being constructed in any manner familiar to workers in the metal art, against which the reinforced base portions of the packing members

may abut and prevent abnormal lengthwise separation of the coupling members. This I regard as an important feature of my present improvements.

From the foregoing description it will be apparent that in a simple and inexpensive manner I have provided a practicable and durable coupling, especially adapted for the purposes for which it is primarily intended, to wit, the permitting of flexibility, to a very considerable extent, while constantly maintaining a sealed relation of the parts, the latter being facilitated by reason of the special cup formation of the packing members with the reduced free flange portions of the members disposed in the direction of the flow of material through the pipe whereby the internal pressures are exerted against the free flanges of the packing and within the cup, to forcibly bind the packing against the walls opposed thereby, and which as previously stated, is throughout a substantial area as compared to a line contact owing to the flat engagement of the entire flange h'' of the packing against the coupling member, which said flange faces and over which it works.

Having thus described the invention, what is claimed is:—

1. A coupling of the character described for dredging pipes and the like comprising pipe sections adapted to be connected, one of said sections being provided with an inwardly offset portion to constitute a shoulder, a flexible packing member on the other pipe section adapted to slidably engage the shouldered section, said packing comprising a reinforced base portion and an offset free edge portion adapted to have an extensive surface engagement with the member which it opposes.

2. A coupling of the character described for dredging pipes and the like comprising pipe sections adapted to be interfitted to permit one section to swing relative to an adjoining section, one of said sections being provided with an inwardly offset portion to constitute a shoulder, a flexible packing member on the other pipe section adapted to slidably engage the shouldered section, said packing comprising a reinforced base portion and an offset free edge portion adapted to have an extensive surface engagement with the section which it opposes.

3. A coupling of the character described for dredging pipes and the like, comprising pipe sections adapted to be interfitted to permit swinging movement of one section relative to the other section, means on one of the sections comprising an inwardly projecting flange or ring normally fixed in position with reference to the said pipe section to constitute a rigid abutting shoulder, a flexible packing member on the other pipe section adapted to slidably engage the

shouldered section, said packing having an offset free edge portion adapted to have an extensive surface engagement with the section which it opposes inside of said abutting shoulder, substantially as and for the purpose described.

In testimony whereof I affix my signature in presence of two witnesses.

EDWARD FRANCIS BERRY.
